UNITED STATES PATENT OFFICE.

JOHN C. LOWDON, OF KANSAS CITY, MISSOURI, AND JAMES DIXON, OF KANSAS CITY, KANSAS; SAID LOWDON ASSIGNOR TO SCHUYLER C. ELLIOTT, OF KANSAS CITY, KANSAS.

SMOKE-CONSUMER.

SPECIFICATION forming part of Letters Patent No. 448,530, dated March 17, 1891.

Application filed July 10, 1890. Serial No. 358,263. (No model.)

To all whom it may concern:

Be it known that we, JOHN C. LOWDON, of Kansas City, in the county of Jackson and State of Missouri, and JAMES DIXON, of Kansas City, in the county of Wyandotte and State of Kansas, have invented certain new and useful Improvements in Smoke-Consumers, of which the following is a full, clear, and exact description, reference being had to the accompanying drawings, forming a part of this specification.

Our invention relates to an improved smoke-consumer to be used in connection with locomotive and other furnaces; and our invention consists in features of novelty hereinafter described, and pointed out in the claim.

Figure I is a longitudinal section of a locomotive with our improvement attached. Fig. II is a perspective of our improved deflector. Fig. III is an enlarged detail front view of the furnace-door. Fig. IV is a transverse section showing exhaust-nozzle.

Referring to the drawings, 1 represents a locomotive-boiler with the usual fire-tubes 2. 3 represents the fire-chamber of the locomotive, having a deflector-arch 4.

5 represents our improved concave deflector for assisting in retarding the smoke and gases until they have been consumed. The deflector is provided with corrugations 6 to add to its strength, and is set in the front wall of the fire-chamber just over an opening 7, through which fresh air is admitted to the furnace. The deflector extends inwardly and downwardly to about the center of the fire-chamber. The deflector 5 and arch 4 retard the smoke and gases in the fire-chamber until the major portion of the same has been consumed, the heat taking the course shown by arrows, Fig. I.

8 represents a door by which the opening 7 may be closed, if desired; but it is intended for this door to remain open the most of the time in order to supply plenty of fresh air to 45 the furnace or fire-chamber.

9 represents a door, to which the smaller door 8 is hinged, said larger door having suitable hinges and latch, as shown at 10 11.

12 represents the latch of the door 8, to 50 which is secured a chain 13 for operating the same.

14 represents the smoke-stack, in which there is a central tube or pipe 15.

16 represents a nozzle, through which the 55 exhaust-steam may pass from the cylinders 17 out through said nozzle and the tube 15 in order to increase the draft.

18 represents a vertically-movable sleeve situated on the nozzle 16 near its upper end. 60 By raising or lowering said sleeve on the nozzle the draft may be increased or diminished by permitting a greater or less amount of the products of combustion to pass off through the tube 15. (See dotted lines, Fig. I.) 65

19 represents a set-screw for holding the sleeve 18 at any desired point.

We claim as our invention—

The combination of the boiler 1, flues 2, fire-chamber 3, deflector 5, deflecting-arch 4, 70 doors 8 9, suitable hinges and fastenings on said doors, smoke-stack 14, flue 15 in the smoke-stack, exhaust-nozzle 16, and adjustable sleeve 18 on said nozzle, substantially as described, and for the purpose set forth.

JOHN C. LOWDON.
JAMES DIXON.
